SLIDE CLOSURE

Leo D. Farney, Chicago, Ill.

Application September 18, 1939, Serial No. 295,478

4 Claims. (Cl. 181—22)

The present invention relates to slide closures in compartment partitions, and particularly to electrically operated closures. Specifically it has especial adaptation to confessionals which comprise a confessor's compartment and one or two penitent's compartments. When a penitent enters the confessional it is very desirable to have his compartment closed off from the confessor's compartment until the confessor is ready to hear him, for his own convenience, and also, when the confessor is conversing with another penitent in the other side of the confessional it is necessary that communication with the first penitent be closed off.

An object of the invention is to secure privacy to the occupants when the closure is closed, and to provide sure communication when the closure is opened.

The closure is composed of two members, one fixed and the other movable; each is provided with small openings therein, so arranged that the openings in the movable member will register with those in the fixed member upon operation of the former, and are of such size and position that the largest possible total opening can be obtained while completely closing off all openings when the closure is closed. One of the desirable features therefore is the fact that a very small movement of the movable member is necessary to open the closure. This results in a grill work with sufficient opening to afford communication, since it is undesirable to have a complete opening; and when the closure is closed all openings in the members are closed off, which with the fact that the members are made of soundproof material insures complete privacy.

Another object is to provide lighting means in the penitent's compartment to enable the penitent to enter and leave the compartment at ease. Since it is desirable to have the confessional dark while the penitent and the confessor are conversing, means must be provided to operate the lighting means conveniently. My invention provides means for lighting the penitent's compartment when he is entering and leaving, and for turning off the light during the remaining time with no extra movements or operations on the part of either occupant. I provide switching means arranged so that when the closure is opened the light is turned off, thus leaving it dark when the confessor and the penitent are conversing, and when the closure is closed the light is turned on in the same operation, thus enabling the penitent to leave without stumbling.

Other objects and advantages of the inven-

tion, including combination, arrangement and function of parts, and details of construction, will be apparent as the description of the invention proceeds, which should be taken in conjunction with the accompanying drawings in which:

Figure 1 is a perspective view of a confessional showing the interior of the confessor's compartment and one penitent's compartment and exposing to view the position of my new slide closure;

Figure 2 is a view of the slide closure itself from the penitent's side;

Figure 3 is a view of the slide closure in closed position viewed from the confessor's side;

Figure 4 is a sectional view taken on the line 4—4 of Fig. 3, and looking in the direction of the arrows;

Figure 5 is a sectional view similar to Fig. 4, but with the slide in open position;

Figure 6 is a horizontal section taken on the line 6—6 of Fig. 5;

Figure 7 is a diagram showing the circuit arrangement for operating the slide closure and lighting means;

Figure 8 is a front view of a switching means positioned in the seat in the confessor's compartment, forming a modification of my invention;

Figure 9 is a section taken on the line 9—9 of Fig. 8 looking in the direction of the arrows;

Figure 10 is a modified circuit arrangement to be used in connection with the modification of Figs. 8 and 9;

Figure 11 is a perspective view of the connecting link between the movable slide member and the operating means for sliding the member, and

Figure 12 is a sectional view of a modification of my invention.

Referring to the drawings, in Fig. 1 which shows the confessional as a whole, 11 and 12 designate the penitents' compartments, and 13 the confessor's compartment, with intervening partitions 11' and 12'. This view shows to good advantage the general construction of the confessional, with the confessor's compartment, and a penitent's compartment on either side. In the partition between each two adjacent compartments there is provided one of my improved slide closures. The closure is indicated generally by the numeral 14. In the penitent's compartment as shown in Fig. 1 is a kneeler 16 and an arm rest 17. A lamp is shown at 18 which is utilized to light the penitent's compartment when the penitent is entering and leaving. In the con-

professor's compartment will be seen a seat 19 and an arm rest 20.

It is to be understood that penitent's compartment 12 is similarly provided with a kneeler, arm rest, and light as is compartment 11, although it is not shown since the arrangement of fixtures is obvious. Also it is quite obvious that the slide closure in each partition extends through the partition and can be seen from either side of the partition. Thus closure 14 seen in compartment 11 can also be seen in compartment 13 on the side of the partition away from the observer.

Figure 2 is an enlarged view of the slide closure as viewed from the penitent's side and showing to better advantage the details of construction. Facing the penitent is the stationary member of the closure. This member is provided with holes 22 which register with corresponding holes in the movable member as will be more apparent as the description proceeds. At each side and at the bottom of the closure are strips 23, which, with strips 31 on the opposite side of the closure, form a retainer for the stationary member and a channel in which the movable member slides. At the top is a cover plate 24 which also serves as a retainer for the stationary member 21 and is of sufficient height to conceal certain elements of construction which will be described later. It is readily apparent that the whole structure is mounted in the partition 11'. Below the structure is an arm rest 17 mounted on the partition by means of brackets 25.

Figure 3 is a view similar to Fig. 2 but from the confessor's side. Certain outer trimmings are omitted from this figure to show the inner construction, but they may be easily supplied from Figs. 4, 5 and 6. On this side are mounted strips 23', (see Figs. 4, 5 and 6), which are the counterpart of strips 23, and form a retainer for the stationary and movable members of the closure. Also on this side of the closure is a cover plate 24' identical with cover plate 24 and serving the same purpose. This view shows the cut-out portion of the partition 11', shown generally as 28. Facing the observer from this side is a movable member 29 which is adapted to move vertically in the cut-out portion 28. The movable slide member 29 is of proper width to fit snugly in the cut-out portion 28 and yet loose enough to slide easily. On each lateral side of the opening 28, and on the same side of the closure, is a cleat 31 attached to the partition 11' by screws or otherwise as desired. Between these cleats and the stationary member 21 are formed channels in which the movable member of the closure is adapted to slide.

Fig. 4 should be considered in connection with Fig. 3 to show the relative position of parts. In considering this view the reason for the cleats 31 will be apparent: the stationary member of the closure is positioned near the edge of the partition nearest to the penitent's side and the movable member 29 is positioned in the center of the partition. In this location the movable member may bear on one side against the stationary member, but since there is a considerable space between the movable member and strips 23' it becomes necessary to supply the cleats 31 to fill this space.

An electromagnet 33 is secured to the top of the opening 28 and operatively connected with the movable member 29 so as to operate the latter on energization of the electromagnet. The solenoid 34 of the electromagnet projects downwardly therefrom and is provided with threads

35 on which is secured a fork 36. A bolt 37 projects through the fork 36 and through the movable member 29 of the closure and thus a connection is made between the electromagnet 33 and the movable closure member 29. At the top of the movable member 29 and on either side thereof is a plate 39 secured thereto by rivets 42 and through which the bolt 37 passes. This is to assure that the movable member will not be cut through as may be in the case when a single bolt is used without plates 39 and the movable member is made of soft material. It will thus be seen that with the movable closure member 29 positioned in the center of the partition directly below the electromagnet a direct pull is exerted on the movable member without distortion or binding.

As previously mentioned, the stationary member 21 is provided with holes 22 located at certain intervals; likewise, in the movable member 29 are holes 38 of the same size and located at the same intervals as holes 22. When the movable member 29 is in its lowered position as shown in Figs. 3 and 4, the holes in the two closure members are in staggered relation with respect to one another and the closure is completely closed. This is accomplished by making the holes smaller than the distance between them. The two members, 21 and 29, are made of pressed fiber, wood, or any other material, including metal. A particular material may be used to secure sound-proof members, or a more durable material may be desired; but for whatever purpose, the material used is not of the essence of the invention and consequently I do not intend to be limited to any particular material.

It is contemplated within the scope of my invention to use as may be required or desired two or more electromagnets instead of only one, as it may in certain instances require more than one to supply the necessary lifting force without noise, overheating or vibration.

Figure 5 is a view similar to Fig. 4 and shows the movable member in its raised position with the holes in the two closure members in registry with one another. The holes are of such size and are so spaced that a maximum opening is accomplished with a minimum of movement of the movable member 29. The closure will be in open position only when the electromagnet is energized, and will automatically drop to closed position when the electromagnet is de-energized.

Attached to the bottom of the cut-out portion 28 are cushions 40, composed of rubber or other suitable cushioning material. These cushions prevent contact between the movable member 29 and the partition 11', and consequent noise, on release of the member 29. The cushions 40 may be glued to the partition, or they may be recessed into the partition and then glued, as may be desired. In a like manner cushions 41 are secured to the upper extremity of the cut-out portion 28 so that on upward movement of the movable member 29 the contact is cushioned. As previously mentioned, the fork 36 is secured to the solenoid 34 by means of threads 35; by this feature accurate registry of the holes 38 in the movable member 29 with the holes 22 in stationary member 21 can be accomplished. On actuation of electromagnet 33 the movable member 29 is raised to its extreme upper position in contact with pads 41 and if the pads are not in accurate position so that the holes in the two members do not register, the fork 36 may be screwed up or down as the case may require, so that the holes will register.

Below the closure are two arm rests 17 and 20, for the convenience of the occupants, referred to in connection with Fig. 1, one secured to either side of partition 11'. These are secured in position by means of brackets 25 screwed to partition 11' (or 12') and the arm rests, or otherwise secured as desired.

In Figure 7 I have shown the circuit arrangement for operation of the slide closure. The usual source of current as used in churches is supplied at 44. At 45 is indicated generally a switch, having two contacts 46 and 47. When the switch is in the position shown in Fig. 7, with contact 46 closed, current is supplied through wire 48, through the switch 45 and contact 46, through wire 49 and the solenoid 33, and returning through wire 50, thus completing the circuit. When the switch is in the other position, i. e., with contact 47 closed, current passes through wire 48, through switch 45 and contact 47, wire 51 and the light 18, and returning through wire 50, thus completing the circuit. This accomplishes the object stated above, that when the penitent enters the confessional the closure is closed and the light 18 is lighted, i. e., with contact 47 closed. When the confessor is ready to hear him he throws the switch 45 opening contact 47 and closing contact 46, thus switching off the light and operating solenoid 33 and thereby opening the closure. The application of this circuit to the structure is shown in Fig. 3.

In Figs. 8 and 9 I have shown a modified switching arrangement. When the confessional is not in use at all obviously all lights might well be out, and the solenoids operating the closures not in operation. To accomplish this result I have provided the switching arrangement shown in this modification, which can be fitted into the circuit shown in Fig. 7; in the circuit of that figure either the solenoid or the light will be in operation until a positive act is made to switch off the whole circuit. The circuit including the present modification is shown in Fig. 10. The seat in the confessor's compartment is shown at 55, and hinged to the back wall of the compartment by hinges 56. Strips 57 are secured to the partitions 11' and 12' to support the seat 55 when it is occupied. Springs 58 are recessed into the strips 57 and serve to raise the seat from its lowered position when it is unoccupied. Contacts 59 are provided, one on the seat 55, and the other recessed into the strip 57, the lower one being biased upwardly by spring 60 to secure firm contact and yet allow the seat to rest solidly on the strips 57. Attached to the front of the seat 55 is a cover plate 61 to conceal the strips 57. This switching arrangement is inserted at 62 in the circuit shown in Fig. 10, which is otherwise identical with the circuit of Fig. 7. This arrangement allows automatic operation of the circuit, and insures that the circuit is not in operation when the confessional is not occupied, because when the confessor arises from his seat the lights are extinguished if any are burning, and will de-energize the solenoids if they are left in operation, but it is not likely that they will be left in operation because when the penitents' compartments are unoccupied the closures will be closed.

Also in this embodiment may be included additional switching means 66 which may be connected with a light 67 placed on the outside of the confessional over the confessor's compartment. This is simply to indicate whether or not the confessor is in the confessional.

Figure 11 shows the fork 36 and in this view 75

can be seen resilient contact means 71 interposed between the slidable member 29 and the electromagnet 33. Vulcanized rubber or other similar resilient material is inserted in the opening in the member 36 to prevent vibration of the solenoid from being transmitted to the slidable member 29 when the electromagnet is in operative position.

In Fig. 12 I have shown a modified form of closure with mechanical operating means. I have shown the usual stationary member 21 and slidable member 29, positioned in the partition 11' and held in place by strips 23 and 23', and cleats 31. Near the lower part of the strip 23' on the confessor's side is a boss 75 projecting outwardly from strip 23'. A lever 76 is pivoted at 77 and the inner end is secured to movable member 29. A spring 79 is attached to the inner end of the lever at 81 and at a point near the outer edge of the boss 75 at 82. Thus a toggle arrangement is secured by means of the spring since a line drawn from 81 to 82 will fall either below or above the pivot point 77 and maintain the lever in whatever position it is placed. The member 29 is raised by pressing down on lever 76 and when it is in position the spring 79 will keep it there; the same is true when the member is in its lower position.

I do not intend to be limited to the specific details herein shown and described, but contemplate to include within the scope of the invention all substitution of equivalents and changes in details of construction and arrangements of parts to fit particular conditions.

What I claim therefore and desire to secure by Letters Patent is:

1. In a slide closure of the class described, a frame, a stationary member with openings therein mounted in the frame, a movable member with openings therein mounted in the frame in sliding engagement with said stationary member and adapted to be raised and lowered, the openings in the movable member being out of registry with the openings in the stationary member when the former is in its lowered position and in registry therewith when the former is in its raised position, spacing means in said frame engaging said movable member on the side opposite said stationary member, said stationary member and said spacing means positioning said movable member in the vertical medial plane of said frame, and means mounted on said frame above and connected to said movable member and in the plane thereof for raising said movable member.

2. In a slide closure of the class described, a frame, a stationary member with openings therein mounted in the frame, a movable member with openings therein mounted in the frame in sliding engagement with said stationary member and adapted to be raised and lowered, the openings in the movable member being out of registry with the openings in the stationary member when the former is in its lowered position and in registry therewith when the former is in its raised position, spacing means in said frame engaging said movable member on the side opposite said stationary member, said stationary member and said spacing means positioning said movable member in the vertical medial plane of said frame, means mounted on said frame above and connected to said movable member and in the plane thereof for raising said movable member, and cushioning means at the upper and

lower extremities of the range of movement of the movable member.

3. In a slide closure of the class described, a frame, a stationary member with openings therein mounted in said frame, a movable member with openings therein mounted in said frame and adapted to be raised and lowered, said openings in the movable member being out of registry with said openings in the stationary member when the former is in its lowered position and in registry therewith when the former is in its raised position, electromagnetic means mounted on the frame and connected to said movable member for raising said movable member, cushioning means acting between said electromagnetic means and said movable member for eliminating the transmission of vibrations from said electromagnetic means to said movable member, and cushioning means positioned in the path of movement of said movable member for limiting the upward movement of said movable member.

4. In a slide closure of the class described, a frame, a stationary member with openings there-

in mounted in the frame, a movable member with openings therein mounted in the frame in sliding engagement with said stationary member and adapted to be raised and lowered, the openings in the movable member being out of registry with the openings in the stationary member when the former is in its lowered position and in registry therewith when the former is in its raised position, electromagnetic means mounted on the frame and connected to said movable member for raising the movable member and for retaining it in raised position, cushioning means acting between said electromagnetic means and said movable member for eliminating the transmission of vibration from said electromagnetic means to said movable member, second cushioning means at the upper extremity of the range of movement of said movable member, and adjustable connection between said electromagnetic means and said movable member so that the openings in said stationary member and said movable member are in registry when said movable member is in its raised position.

LEO D. FARNEY.
